[57] **ABSTRACT**

A tray in the shape of a plate manufactured from fiber pulp or a similar material, particularly an egg tray is provided with means for preventing the walls of recessed portions from being jammed one on the other when stacking the plates. Between a number of recessed portions, a number of ridges or dams, disposed higher than the dams or ridges between the other recessed portions are provided. The higher dams or ridges are so distributed all over the plate surface and according to such a pattern that mutually equally designed plates, only when turned at an angle of 180°, can be so placed one on top of the other that then only the higher ridges or dams serve as supports between two successive plates.

FIG. 3

TITLE MOLDED TRAYS WITH MEANS TO PREVENT JAMMING

This application is a continuation of U.S. Pat. application Ser. No. 795,000, filed Jan. 29, 1969.

From practice plates molded from fiber pulp are generally known, such plates being formed with mutually spaced conical or somewhat cone- or pyramid-shaped cavities, the latter separated one from the other by equally conical and/or somewhat cone- or pyramid-shaped embossments. These plates or trays are generally known as so-called egg-trays and they serve for shipping and storing a great number of eggs, whereas the eggs are protected then against mutual contact and in consequence thereof against possible damage by the above mentioned embossments.

The material from which these egg-trays are made, is very light and therefore in this respect does not cause any difficulty in the transportation of the empty material. On account of their shape the trays are relatively voluminous which does create transportation problems. However, in practice the empty trays may be piled one on top of and partially into the other and in doing so the hollow embossments on the lower side of piled up plates or trays alternately receive the embossments of an underlying equably designed plate.

However, the fact that the embossments are conical or correspondingly shaped, forms a serious practical difficulty since then the embossments will jam one in the other and it will not be possible to easily take the trays separately from a pile.

The mentioned difficulty has already been known, and various proposals have been made for preventing the cup-shaped parts of the plates from engaging too deeply with one another and from their subsequent mutually jamming. It is known to form a small massive block or cam in some corners of the tray which block or cam serves as a stopping cam and should prevent the cups from telescoping too far. It is well known to provide ridges in the trays with vertical walls of such a narrow shape, that during the molding of the trays they are saturated with pulp mass. As the trays are piled up the so formed massive ridges will be disposed one on the other and they also keep the cups separated from each other. A serious disadvantage connected with the manufacture is attended with these known processes. In consequence of the narrow limitations of the ridges or cams, locations are formed in the suction mold, by means of which the plates are molded from fiber pulp, where the fiber mass has some difficulty in releasing itself from the mold. Then, as after the molding the molded plate has to be transferred to the usual transitional mold, the fiber mass will remain in the primary or suction mold and the latter will be clogged. This will lead to irregularly shaped products.

The present invention has as its object the provision of a tray construction which enables the trays to be piled up closely together whereas nevertheless the risk of mutually jamming is prevented. A further object of the invention is to make the necessary provisions for that purpose without any harmful influence upon the manufacturing process. Such provisions, make it possible to maintain practically equal wall thicknesses throughout the trays, and in consequence thereof prevent the risk of clogging up the primary suction molds.

According to the invention, these objects are achieved by the provision of a plate of the type mentioned which has formed thereon a number of dams or ridges between a number of recessed portions. The dams or ridges are disposed at a higher level than the dams or ridges between other recessed portions. The said elevated dams or ridges are distributed over the plate surface asymmetrically according to such a pattern that mutually equally designed plates, when mutually turned at an angle of 180°, can be stacked one on top of the other, that then only the elevated dams or ridges of the lower plate contact with the next upper plate.

It is obvious that for realizing this possibility the pattern in question may be designed in many different ways.

In order to prevent the walls of the cups, which walls are generally rather rough and offer a great frictional resistance, from contacting one another, turning the plates mutually at an angle of 180° is a requirement, this with a view to the uniformity in manufacturing of the plates being stacked. This however is the manufacturer's concern who has to see to the transportation of the plates, and the manufacturer can easily take the necessary measures for proper stacking of the plates. Then the user has the great advantage of easily releasing the plates one from the other.

Now the invention will be explained with the help of the accompanying drawings which illustrate one embodiment of the invention.

BRIEF DESCRIPTION OF THE DRAWINGS

FIG. 1 is a plan view of a tray in accordance with the present invention;

FIG. 2 is a cross-sectional illustration taken along line II—II in FIG. 1; and

FIG. 3 is a cross-sectional illustration taken along line III—III in FIG. 1.

The figures show a tray according to the invention. The trays are represented in the usual way with the embossments 1 separating recesses 2 turned upwards. Between these embossments the normal dams 3 having a first height are disposed. According to the invention, higher dams 4 are also provided and which have a more narrow face, since the faces 5 and 6 thereof taper further upwardly. At the points indicated shadedly the elevated dams 4 are disposed asymmetrically according to such a pattern that similar plates, when at an angle of 180°, are so disposed one on the other that the elevated dams 4 of the lower tray contact only the normal dams 3 of the next upper plate or tray.

If a pattern is chosen wherein in a row a dam is alternately higher with respect to its adjacent dam, it will be clear that all dams of two successive plates will rest one upon the other. In case a different pattern is applied and e.g. in a row a number of dams remain at the same level, it will be necessary in turning at an angle of 180° to have the higher dams face the deeper recesses which have resulted from disposing the higher dams in the other plate. So a number of plates are capable of remaining absolutely free of one another.

I claim:

1. In a set of rectangular molded pulp trays, particularly for use in packing objects such as eggs, wherein each of said trays has an upper object-receiving surface

comprising a plurality of parallel rows of raised embossments, a plurality of parallel rows of object-receiving recesses, said rows of recesses being alternately arranged between said rows of embossments, said embossments being joined by and said recesses being separated by integrally molded dams arranged in rows parallel to an edge of said tray and having means for preventing the walls of said embossments and said recesses from being jammed when said trays are stacked one upon the other:

the improvement wherein said means comprises a first plurality of said dams extending upwardly with respect to said surface for a first height, and a

second plurality of said dams extending upwardly with respect to said surface of a second height greater than said first height in alignment with said first plurality of dams in said rows, said second plurality of dams being positioned so that the pattern thereof on said surface of said tray is asymmetrical with respect to a center line of said tray such that when a first of said trays is rotated 180° and stacked on a second of said trays, said first plurality of dams of said first tray aligns with and rests on only said second plurality of dams on said second tray.
